M. J. RICHARD.

HARROW.

APPLICATION FILED APR. 21, 1917.

1,237,556.

Patented Aug. 21, 1917.

Inventor

MARTIN J. RICHARD

By *Watson E. Coleman*
Attorney

UNITED STATES PATENT OFFICE.

MARTIN J. RICHARD, OF RAYNE, LOUISIANA.

HARROW.

1,237,556.

Specification of Letters Patent. Patented Aug. 21, 1917.

Application filed April 21, 1917. Serial No. 163,620.

To all whom it may concern:

Be it known that I, MARTIN J. RICHARD, a citizen of the United States, residing at Rayne, in the parish of Acadia and State of Louisiana, have invented certain new and useful Improvements in Harrows, of which the following is a specification, reference being had to the accompanying drawings.

This invention relates to certain improvements in harrows and is an improvement on the device as disclosed in my prior Patent No. 1,134,639, dated April 6, 1915; and it is an object of the invention to provide a harrow of this type with novel and improved means for preventing the soil being treated from falling out of the harrow and thus failing to be pulverized.

It is also an object of the invention to provide a device of this general character having novel and improved means whereby the circular or revolving movement of the harrow proper may be attained with a minimum of frictional resistance.

The invention consists in the details of construction and in the combination and arrangement of the several parts of my improved harrow whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be the better understood, I will now proceed to describe the same with reference to the accompanying drawings, wherein—

Figure 1 is a view in top plan of a harrow constructed in accordance with an embodiment of my invention;

Fig. 2 is a view in side elevation of the harrow as herein disclosed;

Fig. 3 is a view in transverse section taken through the beam and illustrating in detail the bracket depending therefrom; and

Fig. 4 is a fragmentary view partly in elevation and partly in section taken through the marginal portion of the device as herein embodied.

As disclosed in the accompanying drawings, 1 denotes a beam provided at one extremity with means 2 whereby draft rigging may be suitably engaged in order that the device may be drawn over the ground.

Disposed vertically through the beam at a predetermined point intermediate the length thereof is a shaft 3 extending upwardly from the hub 4. The shaft 3 extends above the beam 1 and said extended portion is provided with a transverse pin 5 affording oppositely directed trunnions upon which are loosely mounted the wheels 6 contacting with the annular plate 7 lying upon the upper face of the beam 1 and surrounding the extended portion of said shaft 3 whereby it will be perceived that the rotation of the shaft 3 will be effected with a minimum of frictional resistance.

Concentric to the lower end portion of the hub 4 and in spaced relation thereto is the annular member 8 substantially Z-shape in cross section, with the upper flange of which is adapted to contact the gage wheel 9 mounted on the outer extremity of the arm 10 operatively engaged, as at 11, with the annular plate 7 hereinbefore referred to. The arm 10 is disposed substantially perpendicular to the beam 1 and is maintained in such position through the medium of the brace rods 12 secured to the outer end portion of the arm 10 and to the beam 1 at opposite sides of said arm 10.

Mounted upon the arm 10 is the weighted member 14 adjustable longitudinally of said arm 10 whereby it will be perceived that the action of the gage wheel 9 upon the upper flange of the annular member 8 may be regulated.

The annular member 8 is operatively tied or connected with the hub 4 through the medium of the radiating spokes 15 formed of angle iron and suitably engaged with the annular member 8 and the spokes 15 are the ground engaging members 16.

Interposed between the outer end portions of adjacent spokes 15 are the arcuate plates 17. These plates 17 are relatively broad and have their outer edges substantially in contact with the vertical or intermediate portion of the annular member 8. The plates 17 serve effectually to prevent the soil from falling out of the harrow and thus failing to be pulverized and in practice this has been found to be of especial importance. It has also been found of manifest advantage to have the arm 10 operatively engaged with the shaft 3 above the beam 1 as this arrangement permits the harrow to run lighter, work better, turn faster and to be more easily con-

structed than the form of harrow as embodied in my prior Patent No. 1,134,639, dated April 6, 1915.

The extremity of the beam 1 opposite that provided with the engaging means 2 has operatively engaged therewith the wheel 18 which is adapted to ride upon the upper flange of the annular member 8. It has also been found of advantage to provide the beam 10 at a predetermined point inwardly of the engaging means 2 with the depending bracket 19 herein disclosed as substantially U-shape in form and which contacts with the upper flange of the member 8 when the harrow is not in use.

From the foregoing description, it is thought to be obvious that a harrow constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. A harrow of the class described comprising a beam, a hub positioned below the beam and provided with a shaft extending upwardly through the beam and terminating

thereabove, anti-friction means carried by the upper portion of said shaft and coacting with the upper face of the beam, a member surrounding the hub and connected thereto, 40 a wheel carried by the beam and riding upon the member, and ground engaging means carried by said member.

2. A structure as specified in claim 1, an arm operatively engaged with the upper portion of the shaft, and a gage wheel carried by said arm and riding upon the member.

3. A structure as specified in claim 2, means interposed between the beam and arm for maintaining said arm substantially in a 50 fixed position relative to the beam.

4. A structure as specified in claim 1, the anti-friction means consisting of trunnions radiating from the upper portion of the shaft, and wheels mounted on said trunnions.

5. A harrow of the class described comprising a beam, a hub positioned beneath the beam and provided with a shaft extending therethrough, a member surrounding the hub and operatively connected thereto, a wheel carried by the beam and traveling upon said member, and plates extending inwardly from the member, said plates being relatively broad.

In testimony whereof I hereunto affix my signature in the presence of two witnesses.

MARTIN J. RICHARD.
